UNITED STATES PATENT OFFICE.

GLENN E. McFADDEN, OF LAKEWOOD, OHIO, ASSIGNOR TO ALFRED VESTER SONS, INC.,
OF PROVIDENCE, RHODE ISLAND, A CORPORATION OF RHODE ISLAND.

DESIGN FOR A LOOP FOR LIGHTING FIXTURES.

Application filed October 10, 1923. Serial No. 7,464. Term of patent 7 years.

To all whom it may concern:

Be it known that I, GLENN E. McFADDEN, a citizen of the United States, and residing at Lakewood, in the county of Cuyahoga and State of Ohio, have invented a new, original, and ornamental Design for a Loop for Lighting Fixtures, of which the following is a specification, reference being had

to the accompanying drawing, forming part thereof.

The drawing is a plan view of a loop for lighting fixtures showing my new design.

I claim:

The ornamental design for a loop for lighting fixtures as shown.

GLENN E. McFADDEN.
